US00D722636S

(12) **United States Design Patent**
Ishibashi et al.

(10) **Patent No.:** US D722,636 S
(45) **Date of Patent:** ** Feb. 17, 2015

(54) **PROJECTOR**

(71) Applicant: **Hitachi Maxell, Ltd.**, Osaka (JP)
(72) Inventors: **Atsushi Ishibashi**, Tokorozawa (JP);
Takashi Yamamoto, Kodaira (JP);
Kazumasa Ueoka, Yokohama (JP);
Toshiyuki Moriya, Tokorozawa (JP)

(73) Assignee: **Hitachi Maxell, Ltd.**, Osaka (JP)

(**) Term: **14 Years**

(21) Appl. No.: **29/467,778**

(22) Filed: **Sep. 24, 2013**

(30) **Foreign Application Priority Data**

Mar. 27, 2013 (JP) 2013-006828

(51) **LOC (10) Cl.** 16-02

(52) **U.S. Cl.**

USPC D16/230; D16/225

(58) **Field of Classification Search**

USPC D16/221, 225, 230-231, 234-235, 205,
D16/208; D21/514; 352/34, 242; 353/115,
353/119, 122
